JOHN F. KELLY, OF PITTSFIELD, MASSACHUSETTS.

MUSICAL INSTRUMENT.

1,078,627.

Specification of Letters Patent.

Patented Nov. 18, 1913.

Application filed April 29, 1911. Serial No. 624,237.

To all whom it may concern:

Be it known that I, JOHN F. KELLY, a citizen of the United States of America, residing at Pittsfield, in the county of Berkshire and State of Massachusetts, have invented new and useful Improvements in Musical Instruments, of which the following is a specification.

This invention relates to improvements in means or devices for producing musical tones or sounds of a single pitch.

It consists, in general, of a metallic member or body of a suitable size and thickness that is adapted to respond to the electromagnetic influences of electrical currents. Such a body, therefore, must be composed of some substance that possesses magnetic properties, as iron, steel, or some alloy that possesses them.

It is a well-known fact in electrical science that sheets and rods of iron or steel will become highly magnetized, either temporarily or permanently, when brought within the field of an electric current, and that magnets possess the property of strongly attracting or repelling such magnetic substances. With these facts in mind, I have conceived the idea of causing plates of magnetic substances to be vibrated by the periodic attraction of electromagnetic devices to produce musical sounds. It is also a well known fact that the surface of thin plates or disks of metal or other substances, as glass, when set into vibration by means of the stretched string of a bow do not vibrate at all points; or, in other words, there are nodal lines or points at which no vibration occurs. These nodal lines are known as Chladni's rings and are not as a rule symmetrical in form with respect to the center of the plate, as for example the nodal lines on the upper surface of a circular plate with free unsupported edges are not always concentric with relation to its geometric center,

but are more or less distorted from the true circle; in fact, they are often elliptical in form. Such irregular arrangement of the nodal lines is due to the uneven or non-uniform arrangement of the molecules of the plate; or, in other words, to the non-homogeneous condition of the material composing the plate. Theoretically these lines should be symmetrical in form and in a definite radial position with respect to the center, but on account of such condition or arrangement

of the molecules they do not conform to the theory.

One object, therefore, of my improvement is to produce a sonorous or musical producing plate in which the nodal line may be fixed and practically all others destroyed, that is to say, to produce in such a body a result which would be produced if the molecular arrangement of the molecules in the body were homogeneous throughout.

Another object is to produce a structure that will only respond to a definite number of magnetic vibrations, and thus prevent its being vibrated by a neighboring body in which magnetic disturbances are present.

With these objects in view, reference is made to the accompanying drawings, forming a part of this specification, in which,

Figure 1 is a plan view of a circular plate representing the sound producing body in which a number of radial slits are formed which extend from the free edge toward the center but not far enough to intersect. Fig. 2 is a sectional side view of Fig. 1 showing electromagnetic means located below the plate with one of its poles in close proximity thereto; also a ring surrounding the electromagnetic means and attached to the lower side of the plate. Fig. 3 is a modification of the electromagnetic devices for attracting the plate and comprises a transformer construction. Fig. 4 is a further modification of the electromagnetic device and comprises a simple make and break device in the circuit which surrounds the core of the electromagnet, and Fig. 5 is a modification of the electromagnetic device in which the plate itself is employed to open and close the circuit. Fig. 6 is a modification of the structure of the plate in which the nodal ring element is omitted, the plate being slotted so as to produce an integral ring of metal therein.

Referring to the drawings in detail, a designates the sonorous plate which is to produce the musical sounds when the same is caused to vibrate. This plate is composed of some highly magnetic material, as iron or steel, or possibly some magnetizable alloy may be employed. It is of suitable thickness for the purpose of producing a definite tone when caused to vibrate a definite number of times per second. Preferably this plate is circular in form, and is provided with a plurality of radially arranged slits,

as shown at *b*, which extend far enough toward the center so that a fairly narrow neck of metal is left in the body, as indicated at *c*, but the center portion of the plate is left unslotted in order to afford enough metal to permit or allow the plate to vibrate as a one piece member or body, and not as a reed element. The electromagnetic device which is designated at *d* powerfully attracts the plate *a* when excited and consists of a core member *e* of soft iron wires and a winding *f*. A suitable source of electrical energy is employed to furnish current to the windings, as an alternator, indicated at *g*. The periodicity of the alternator depends upon the rate of vibration that is to be imparted to the plate *a*. One of the poles of the core member *e* is arranged in close proximity to, and below, the center portion *h* of the plate. *i* designates a ring member that is provided with a beveled or knife edge *j* which is secured to the under side of the plate *a* in some suitable manner, as by brazing or soldering. The diameter of the ring, as measured at the beveled edge *j*, is such as to agree with the diameter of the nodal circle of the plate, or the circle at which there is practically no vibration of the molecules. The radius of this nodal circle is practically 0.68 of the radius of the disk, as experimentally determined.

As stated above, the nodal lines of a vibratory plate, by reason of the non-homogeneity of the plate, do not always arrange themselves concentric with the center. By means of the rigid ring *i*, I have found that the nodal circle of the plate can be made to follow or conform practically to a true circle when the plate is vibrated to produce a musical sound. By using the rigid ring *i* a truly circular node in the proper position is secured and by slitting the disk and employing a central excitation the residual effects due to non-homogeneity of the material is reduced. The reed-like elements produced by the slits being tied together at the center of the disk and to the nodal ring *i* (the point of least vibration,) causes the amplitude of each element to vibrate the same amount. The extreme amplitude of vibration is therefore the same for all, and the whole set of reed-like elements must vibrate in unison, or not at all. Cross vibration of each reed element of course is prevented by having a large enough number of these elements until the desired result is secured for the whole disk. As a means of producing this vibration, the electromagnetic device shown herein is employed. It will therefore be seen that when this plate is attracted by means of the core member *e* being energized, it will be placed in a state of vibration, the center and outer portions moving or vibrating in opposite directions. The use of the ring *i*, and the slitting of the disk therefore, serves to ob-

tain two definite results—first, the nodal circles will be confined to one, all of the others being practically destroyed; and, second, the plate is made to act as if the molecules were arranged in a homogeneous manner throughout, whereby the nodal line which is formed is practically a true circle. 70

For producing a change in the magnetic condition of the core member *e*, I do not limit myself to the device shown in Fig. 2, 75 wherein currents from an alternator of suitable frequency are employed in the windings *f*. In Fig. 3, a transformer or induction coil *k* is employed between the alternator and the windings of the electromagnet. In Fig. 4 a battery *m* is used and a simple make and break device *n* is used to open and close the circuit to the windings *f*. In Fig. 5, the plate itself is caused to open and close the circuit, and one way of accomplishing this is 80 to provide the plate with a finger *o* which is adapted to engage the adjustable screw *p*. *q* indicates a switch device to which one terminal of the battery *r* is connected, its other terminal being connected to the winding *f*, 85 and the other terminal of the winding to the ring *i*, which completes the current through the plate to the finger *o*.

In the device which I employ, the dimensions of the ring *i* is such that only one nodal circle is produced, or under consideration, and thus only a single tone is produced by 90 the plate. 95

On account of the plate being slotted to cause the plate to vibrate as a homogeneous body, and the use of the ring *i* to limit and confine the production to only one nodal ring, it is possible to employ several plates in close proximity to each other without there being any mutual disturbance. It is therefore possible to employ or group a series of such plates together to construct a musical instrument that will furnish all of the musical notes desired; as for example, the substitution of these plates for pipes in an organ. 100 105 110

In Fig. 6 the plate *a*, instead of having continuous slits cut therein, as shown at *b*, Fig. 1, is formed with a break leaving a narrow neck of metal *s* interposed between the adjacent ends of the long and short slits *t* and *u*. This neck of metal is located on the nodal line or circle and coincides with the diameter of the ring element *i* shown in the other figures. The formation of the plate *a*, shown in Fig. 6, produces the 115 same results as set forth above under the construction shown in the other figures, that is it causes the plate to vibrate as if it were a homogeneous mass throughout. The series of neck portions *s* are, in effect, a ring element. 120 125

What I claim, is:—

1. In a device to produce a musical tone, the combination of a vibrating member, rigid means in direct contact with and 130

secured thereto and positioned to coincide with a nodal line of the member, and means to vibrate the member, whereby said member may vibrate about the rigid means as a support.

2. In combination, a sonorous member which is capable of producing a single tone, said member comprising a single, slotted plate, means to definitely position a nodal line in the plate, and devices to vibrate the plate.

3. In combination, a magnetizable sonorous member which is capable of producing a single tone, said member comprising a slotted plate, means to definitely position a nodal line in the plate, and electromagnetic devices to vibrate the plate.

4. A sound-producing device, comprising a slotted vibratory member, rigid means secured to said member to define the principal nodal line in said member, and means to vibrate the member.

5. An electromagnetic sound producing

device comprising a magnetizable plate, a ring attached to the plate and coinciding with a nodal line, and magnetic means to vibrate the plate.

6. An electromagnetic sound producing device comprising a slotted magnetizable plate, a ring attached to the plate and coinciding with a nodal line, and magnetic means to vibrate the plate.

7. In combination, a vibratory magnetizable plate, a ring element provided with a knife-edge and secured thereto, and an electromagnetic device to vibrate the plate.

8. An electrical monophone device comprising a slotted plate, a ring secured thereto to position a nodal line therein, and an electromagnetic device to vibrate the plate, whereby the plate will vibrate in unison with the said device.
